UNITED STATES PATENT OFFICE

2,354,415

ADJUSTABLE EYESHIELD

Raymond G. Woodard, East Orange, N. J., assignor to Standard Safety Equipment Co., a corporation of Illinois

Application April 30, 1941, Serial No. 391,195

1 Claim. (Cl. 2—8)

This invention relates to a protective device for the human eyes and face, and more particularly to an improved harness for adjustably supporting a transparent eye-shield on the head of a wearer.

The primary object of the invention is to provide an improved adjustable support for a face and head protective device of the character shown in Bowers Patent No. 2,194,492, issued March 26, 1940.

A further object of the invention is to provide a flexible brow-band on which is mounted a relatively stiff or rigid eye-shield which may be adjusted forwardly or rearwardly to suit the convenience of the wearer while the flexible brow-band is in position. The adjustments can be made without removing the harness and without materially distorting the arcuate head-band or the protective face piece.

The invention is illustrated in a preferred embodiment in the accompanying drawing, in which—

Figure 1 is a side elevational view, showing the eye-shield carried by a harness attached to a man's head; Figure 2, a fragmentary top plan view of the same; and Figure 3, a fragmentary sectional view, taken as indicated at line 3 of Figure 1.

In the embodiment illustrated, an arcuate head-band 4 is made of a relatively heavy and stiff cardboard. Each of its ends is provided with a pair of slots 5 through which the flexible brow-band may be threaded. A relatively stiff eye-shield has a transparent window 6 enclosed in a metal protective frame 7 and attached to a supporting sector 8 by means of headed cotter pins or fasteners 9. The sector 8, if desired, may be continued upwardly, as indicated at 10, to provide a top shield for the forehead and glasses of the wearer. The sector 8 is pivotally connected to the head-band 4 by spring pivots 11. The pivots 11 are arranged so that the eye-shield may be swung upwardly over the head-band, if desired.

The brow-band preferably comprises a strip of elastic material 12 which is threaded through the slots 5 in the head-band and is connected at its ends to form a ring by means of a simple 5 adjustable garter fastener 13. If desired, the front of the brow-band may be provided with a sweat-band 14.

It has been found in practice that workmen wearing a substantially rigid eye-shield of this 10 type like to keep it as close to their faces or eye glasses as possible in order to obtain the maximum protection. As the devices are often used by several different workmen, it is important that a forward and rearward adjustment can be 15 made as easily as possible when the device is on the head of the wearer, for it is only in this position that the desirable adjustment can be ascertained. Accordingly, with the present invention it is merely necessary to adjust the length of 20 the elastic band 12 to the proper head size and the eye-shield and arcuate band 4 may be moved back and forth as a unit to a desired position. In this movement the band 12 slides through all four of the slots in the arcuate member 4.

25 The foregoing detailed description has been given for clearness of understanding only, and no unnecessary limitations should be understood therefrom for some modifications will be obvious to those skilled in the art.

30 I claim:

An adjustable eye-shield harness, comprising: an arcuate transverse head-band of stiff material adapted to rest on the top of the head of a man and extend towards his ears, each end of said 35 head-band being slotted to receive a brow-band; an eye-shield of stiff material pivotally mounted on the end portions of said head-band; and a brow-band adapted to encircle the man's head and threaded through the slots in the head-band 40 so that the eye-shield and head-band may be moved forwardly or rearwardly on the brow-band as a unit.

RAYMOND G. WOODARD.
